UNITED STATES PATENT OFFICE.

SAMUEL A. LEVEL, OF HOT SPRINGS, ARKANSAS.

PROTECTIVE PAD FOR CORNS.

SPECIFICATION forming part of Letters Patent No. 694,762, dated March 4, 1902.

Application filed October 29, 1901. Serial No. 80,438. (No model.)

To all whom it may concern:

Be it known that I, SAMUEL A. LEVEL, a citizen of the United States, residing at Hot Springs, in the county of Garland and State 5 of Arkansas, have invented a new and useful Protective Pad, of which the following is a specification.

My invention relates to protective pads; and its objects are to prevent chafing of parts 10 of the body to prevent the formation of corns over or upon the phalangeal joints of the foot, and in cases where such corns have been formed to provide a protection therefor; to relieve the pressure and rubbing between 15 the toes of the foot and the forward part of the shoe caused by the weight and movement of the body of the person and the foot; to distribute the pressure of the foot upon the inner surface of the shoe and, conversely, the 20 pressure of the shoe upon certain parts of the foot in such a way that the toes of the foot will be protected and relieved from undue pressure and rubbing contact with the shoe; to provide means to hold the toes of 25 the foot in such a position within the shoe that rubbing against each other will be greatly lessened and the formation of soft corns prevented.

With these objects in view the invention 30 consists in the provision of means to prevent or limit the longitudinal movement of the foot within a shoe, thereby to relieve the pressure tending to force the toes against and produce rubbing contact with the forward 35 part of the shoe.

The invention consists, finally, in the novel construction of a protective pad to be herein-after described and claimed.

My invention is illustrated in the accompanying drawings, in which like letters of reference indicate corresponding parts throughout all the figures, and in which—

Figure 1 is a view in perspective, showing a pad constructed according to my invention 5 and applied to a foot in the position of use. Fig. 2 is an inverted plan view of the pad alone. Fig. 3 is an edge view of the same in front elevation.

Referring to the drawings, A represents a 10 pad or cushion of any suitable yielding or resilient material, such as rubber or felt, or it may be constructed of several different ma-

terials arranged in layers or otherwise. One surface of the pad is formed with a plurality of grooves or depressions to conform in this 55 instance to the shape of that portion of the foot upon which the pad is to be placed, whereby the latter is held in position not only against bodily displacement, but against any turning or twisting movement upon the foot. 60 The device is to be placed, preferably, upon the top of the foot, as shown in Fig. 1, immediately over and adjacent to the metatarsal phalangeal joints, and for this purpose the lower surface of the pad is formed with a 65 flattened and slightly curved portion a, extending its length near one edge, this portion merging laterally into a plurality of grooves or depressions a' to fit over the base of the toes and extend out over a part of the length 70 of the first bone of each. This construction performs the double function of holding the pad in position upon the foot and of maintaining the toes in the proper position. In the case of irregular toes, also, it tends to 75 bring the same into the proper position and in many cases causes them to grow straight. The projections a² between said depressions or grooves keep the toes from rubbing together, and thus prevent the formation of 80 corns upon the sides and between the latter. The end depressions a³ are formed incomplete, the material sloping at the outer ends of the pad to form a tapered edge, the upper surface a⁴ being slightly convexed and forming, with the lower surface, a tapered edge, except upon the edge over the toes, which is smoothed off or rounded. The opposite edge a⁵ or that toward the upper part of the foot is preferably curved inwardly to conform to 85 90 the rounded contour of that part of the foot.

In use, the pad is held in position preferably by the stocking of the wearer and the shoe then put on. It will be seen, therefore, that the tendency will be to hold the foot 95 against longitudinal movement toward the front of the shoe when taking a step or when the weight of the body is put upon the foot, thus preventing undue pressure being brought to bear upon the toes to force them 100 into rubbing contact with the shoe. The object and operation of my invention, therefore, are to be carefully distinguished from what are commonly known as corn and bun-

ion plasters or shields, which are constructed to surround the part affected and which in most cases produce an undesirable pressure immediately around and close to said part.

5. In practice my prophylactic will be made in pairs of various sizes to correspond to the various sizes of shoes, and of varying thicknesses to meet the requirements of individual cases and different conditions.

10. Having described my invention, what I claim, and desire to secure by Letters Patent, is—

15. 1. A pad having its under surface formed with projections and depressions to conform to the upper portion of the foot at and adjacent the base of the toes, and an upper surface rounded in conformity with the inner surface of the shoe-vamp in proximity thereto, substantially as described.

20. 2. A pad designed to overlie that portion of the foot at and adjacent to the base of the toes, the under surface of said pad formed with projections registering with the spaces between the toes and conforming to the contiguous toes, substantially as described.

25. 3. A pad of yielding material having its under surface formed with projections and de-

pressions to conform to the upper portion of the foot at and adjacent the base of the toes, and an upper surface rounded in conformity 30 with the inner surface of the shoe-vamp in proximity thereto, substantially as described.

4. A pad having a convexed upper surface, a partly-flattened lower surface, and tapered edges, said lower surface being formed with 35 grooves or depressions extending laterally and merging into the remainder of said lower surface, substantially as described.

5. A pad having a convexed upper surface, a partly-flattened lower surface and tapered 40 edges, said lower surface being formed with grooves or depressions extending laterally and merging into the remainder of said lower surface, and the grooves or depressions adjacent to the ends of the pad being formed incomplete to produce with the upper surface a tapered edge, substantially as described.

In testimony whereof I have signed my name to this specification in the presence of two subscribing witnesses.

SAMUEL A. LEVEL.
